COLLAPSIBLE TRAILER

Joel J. Bouchard, Littleton, Colo., assignor to Jo Bud Inc.,
Englewood, Colo., a corporation of Colorado

Filed Oct. 27, 1966, Ser. No. 4,450

Term of patent 14 years

(Cl. D14—3)

FIG. 1

FIG. 2

FIG. 3

FIG. 4

FIG. 5

FIG. 6

FIG. 1 is a left side elevational view of a collapsible trailer according to my new design, in full extended position;

FIG. 2 is a left front quarter perspective thereof with the trailer in collapsed position;

FIG. 3 is a perspective from the left front quarter with the trailer in full extended position;

FIG. 4 is a perspective from the left rear quarter showing the trailer in collapsed position;

FIG. 5 is a perspective of the trailer from the left rear quarter with the trailer in full extended position; and

FIG. 6 is a right front quarter perspective of the trailer in full extended position.

I claim:

The ornamental design for a collapsible trailer, substantially as shown and described.
